UNITED STATES PATENT OFFICE.

WILLIAM C. B. SPARRY, OF NEW YORK, N. Y.

DESIGN FOR AN UMBRELLA-RUNNER.

SPECIFICATION forming part of Design No. 27,777, dated October 26, 1897.

Application filed September 11, 1897. Serial No. 651,386. Term of patent 7 years.

To all whom it may concern:

Be it known that I, WILLIAM C. B. SPARRY, a citizen of the United States, residing at New York, (Fordham,) in the county and State of New York, have invented or discovered a certain new and original Design for Umbrella-Runners and the Like, of which the following is a specification.

The new design relates to runners for umbrellas, parasols, and shades.

My design provides an improved shape for umbrella and other runners.

The new design is shown in the accompanying drawing, which is a perspective view of an umbrella-runner.

In the drawing, A represents the cylindrical body of the runner; B, its upper extremity; C, its lower extremity, and D an intermediate double serrated annulus.

According to a distinctive feature of the new design the runner has a bulbous-shaped portion E near its lower extremity. This portion is shown as not quite spherical in its shape and having upper and lower semiel-

iptical or substantially semispherical parts a b and intermediate band c. The part a

meets the cylindrical body A at a portion d thereof. The part b terminates at a cylinder e at the lower end C of the runner. The body A is substantially cylindrical and of approximately uniform diameter above its bulbous part E.

The runner embodying the new design is of symmetrical and distinctive form and appearance. The double annulus, being intermediate of the cylindrical body above the bulbous portion, adds to the symmetrical appearance of the whole.

The leading or material feature of my design consists of the cylindrical part A, annulus D, and bulbous portion E.

What I claim is—

The design for umbrella-runners and the like, substantially as set forth and shown in the accompanying drawing.

In witness whereof I have hereunto signed my name in the presence of two subscribing witnesses.

WILLIAM C. B. SPARRY.

Witnesses:

GEORGE H. FRASER,
THOMAS F. WALLACE.
